UNITED STATES PATENT OFFICE

JULIUS A. MEYER, OF ST. LOUIS, MISSOURI

SNARE HOLDER

Application filed January 7, 1929. Serial No. 330,794.

My invention has relation to improvements in drums and is directed more particularly to the holders for the snares.

According to the present method for constructing snare holders, a clamp is provided for holding all of the snares collectively and when one or more snares become loose the entire group must be released and again collectively secured. It is the object of the present invention to provide a snare holder wherein the snares are held in pairs, so that if any one snare becomes loose it is merely necessary to adjust that one together with its mate, the balance of the snares being undisturbed. A further object of the invention is to provide a snare holder embodying means for tightly gripping the snares so that they will not readily become loosened, said means at the same time being adapted for instant release when it does become necessary to make taut any particular snare. These objects together with other advantages inherent in my improved snare holder will be better apparent from a detailed description of the invention in connection with the accompanying drawings, in which:

Fig. 1 is a face view of the drum looking toward the head that has the snares stretched over it, a part of said drum being broken away; Fig. 2 is an enlarged side elevation of the portion of the drum to which the snare holder is affixed; Fig. 3 is a view similar to Fig. 2 showing that portion of the drum on which the snare tensioning device is mounted; and Fig. 4 is an enlarged longitudinal section through the snare holder taken on the line 4-4 of Fig. 2.

Referring to the drawings D represents a drum comprising a metallic shell S and heads H, H' constructed as shown in my co-pending application Ser. No. 215,461, filed August 25, 1927. A group of snares 1, 1 etc. are adapted to be stretched over the head H', said snares being held in place at one end by a snare holder 2 and at the opposite end by a snare adjusting device 3. The adjusting device 3 includes a holder comprising a block 4 having formed in it a series of transverse kerfs 5 and 6, the former being the terminal kerfs and wide enough to receive one snare

1, and the latter being intermediate kerfs which are wide enough to receive two snares (as shown in Fig. 3). One piece of snare wire is sufficient in length to form two adjacent snares, said wire being bent back upon itself (as shown in Fig. 3), and the snares 1, 1 formed from any given wire being placed in adjacent kerfs 5 and 6 so that the partition 7 between kerfs will serve as an anchor for the snares of any particular wire. After all of the snares have been properly positioned in the kerfs of blocks 4, a second block 8 is placed over the block 4 and secured to it by screws 9, 9 which traverse the block 8 and are threaded into the block 4.

The snare holder 2 comprises a base block 10 secured to the shell S by means of screws 11, 11 and a cap 12 which serves as the snare holder proper. The cap 12 is provided with a plurality of juxtaposed grooves 13 of a width slightly in excess of that of two adjacent snares, which are positioned in each groove 13, and securely held therein by a set screw 14 traversing a threaded opening 15 in communication with the groove 13. In order to hold the snares tightly each set screw 14 is advanced through the cap 12 until it firmly engages the pair of snares in the particular groove with which the set screw communicates whereupon said snares will be clamped between the set screw and the base block 10 (as shown in Fig. 4). The cap 12 is held in place against the block 10 by screws 16, 16. When any of the snares 1 become loose the drummer merely loosens the set screw 14 that engages that particular snare so as to entirely free the snare as well as the one next to it occupying the same groove with it, after which he takes hold of these two snares and pulls them until they are again taut after which he tightens the screw 14 so as to hold the snares securely. Obviously, there must be a sufficient amount of the snares projecting beyond the snare holder 2 to take hold of in tightening them, after which the projecting ends are passed into a slot 17 to get them out of the way. The tightening of the snares by twos as effected with my improved snare holder makes this operation very simple, one that can be very quickly performed in com-

parison of the old method of tightening a group of snares at one time.

Of course, the grooves 13 in the cap 12 need not be of a width to receive two snares, but if desired they may be just wide enough to receive one snares, in which case there would also be twice the number of set screws as there must be a set screw entering each groove. However, while this would complicate the construction slightly it would have the advantage that each snares could be individually tightened and separately secured. Other departures may be made in the detail of construction according to the skill of the mechanic constructing the device.

Having described my invention, I claim:

1. A snare holder comprising a suitable base, a snare receiving block adapted to be mounted thereon, said block having a plurality of grooves opening toward the outer face of the block, a pair of snares nested in each groove, and a set screw adapted to enter each groove and impinge on the snares therein to hold them.
2. A snare holder comprising a suitable base, a snare receiving block adapted to be mounted thereon, said block having a plurality of grooves opening toward the outer face of the block, snares disposed in said grooves, and means for separately holding the snares in the respective grooves.

In testimony whereof I hereunto affix my signature.

JULIUS A. MEYER.
